UNITED STATES PATENT OFFICE

163,031

BASE FOR ELECTRIC DRINK MIXER

Gordon W. Florian, Bridgeport, Conn., assignor to Air-Way Electric Appliance Corporation, Toledo, Ohio, a corporation of Delaware

Application January 14, 1950, Serial No. 7,258

Term of patent 14 years

(Cl. D44—1)

To all whom it may concern:

Be it known that I, Gordon W. Florian, a citizen of the United States and a resident of Bridgeport, Connecticut, have invented a new, original, and ornamental Design for a Base for Electric Drink Mixer, of which the following is a specification, reference being had to the accompanying drawing, forming a part thereof.

In the drawing:

I claim:

The ornamental design for a base for electric drink mixer, as shown.

GORDON W. FLORIAN.
